UNITED STATES PATENT OFFICE.

WILLIAM K. TWOMEY, OF CHICAGO, ILLINOIS.

METHOD OF BURNING GAS.

1,167,447.

Specification of Letters Patent. Patented Jan. 11, 1916.

Application filed December 12, 1914. Serial No. 876,998.

To all whom it may concern:

Be it known that I, WILLIAM K. TWOMEY, a citizen of the United States, residing at Chicago, in the county of Cook and State 5 of Illinois, have invented certain new and useful Improvements in Methods of Burning Gas, of which the following is a specification.

This invention pertains to an improved 10 method or process of burning gas in such a manner as to secure complete combustion, the products resulting from such combustion being practically odorless and possessing advantageous sterilizing characteristics.

15 In carrying out the invention in the preferred manner, the gas, initially mixed with air, is burned in a primary burner, from which the unburned portions and the products of the combustion are broken up or subdivided, mixed with more air, heated and confined, to control or steady an otherwise 20 possibly variable pressure. The mixture is burned a second time, and the resulting products are subjected to further mixing 25 and heating, and then to a mechanical subdivision, being at the same time additionally heated. The gases may or may not be allowed to burn again at this time, possibly spasmodically or intermittently, before they 30 are again assembled, mixed, heated, and finally burned. That is to say, the mixture of gas and air is burned successively three, and possibly four, times, with such intermediate treatment as to heating, mixing, 35 subdividing, &c., between the combustions as will result in the eventually complete gaseous combustion.

A burner working on the principle of this invention may be used for the various 40 purposes for which heating gas-burners are ordinarily employed. In order, however, that a full understanding of the invention may be had, I have, in the accompanying drawing, illustrated a burner for room-heating, capable of carrying on the gas combustion in accordance with the principles 45 of this improved method or process.

In this drawing, Figure 1 is a central vertical section of the burner structure; and 50 Fig. 2 is a longitudinal, vertical section on line 2—2 of Fig. 1, the parts being viewed in the direction indicated by the arrows.

Referring to the drawing, it will be observed that the initial or primary burner 9, 55 working on the Bunsen-burner principle, is supplied with mixed gas and air through

the pipes 10 and 11 in the usual manner, the gas, in passing from the one to the other, entraining a proper amount of air. The multiple burner is supported on legs or feet 60 12, which carry a pair of bent bars or standards 13 and 14, on which is mounted a centrally-apertured metallic-plate 15, through the hole of which the vertical inner end of the bent pipe 11 extends, being provided at 65 its top with the burner 9.

A hollow, rectangular, preferably cast-metal, control-box 16 rests on the plate 15, and centrally receives the burner 9. As is illustrated, the top and bottom of the box 70 proper are open, but when in position, as shown, the bottom is covered by the centrally-apertured part of plate 15, and the top is equipped with a cover plate 17, which rests upon and is spaced away from the upper edges of the box by means of short supporting lugs 18, 18, rising from the top edges of the box sides.

An open-bottom, rectangular casing 19, 75 with a longitudinal, horizontal corner 84 burner-opening 20, rests on plate 15 and snugly fits over the sides of the control box 16, being materially longer than the box, as shown in Fig. 2. Above the cover or plate 17, casing 19 is equipped with a horizontal grid or grille 21, made of crossing 85 longitudinal and transverse rods or wires, as shown. This arrangement of parts provides a chamber 22 above the grid or apertured screen, and a compartment 23 below it, 90 accommodating burner 9 and its associated surrounding control-box 16.

The entire structure is covered with an open-front shell or housing 24, and is supplied with an inclined wall 25, which, if 95 desired, may be covered with asbestos or similar material, against which the final flame at the jet-opening 20 may play. This shield 25 prevents air currents from unduly affecting the flame.

100 The method of burning the gas in this appliance is substantially as follows: The mixture of gas and air passing in pipe 11 is burned at the first or primary burner 9 in the usual manner, atmospheric air entering the control box 16 through the admission aperture in plate 15, supplying the fuel with the needed oxygen of combustion, that is supplementing that already mixed with the gas. The control box 16 is preferably sufficiently small so that the flames from the burner 9 play or impinge directly against its 105 110

inner surfaces. The box, being thus relatively small, also regulates or steadies the gas pressure and prevents fluctuations, not only in the pressure, but also of the flames outside of the box. The volume of this box is such that the gas is temporarily retained therein, resulting in its subjected to a high temperature for an appreciable time, which causes decomposition of some of the hydrocarbons preliminary to their combustion. Also the striking of the flames against the inner surfaces of the box maintains the latter at a high temperature, and also effects a mechanical disassociation and commingling of the gases and air. On leaving the box 16 beneath the cover plate 17, the gaseous mixture burns in the chamber or compartment 23, and owing to the circulation and swirling of the gases therein, a further intermixing 20 of the ingredients is brought about. The grid 21 acts to retard the passage of the mixture and to retain it temporarily in the chamber 23, so that it is subjected additionally to the heat of the box 16 and to the 25 flames in the chamber. This chamber 23, being somewhat larger than the box 16, permits the mixture to expand, and, of course, during such expansion it is held at a high temperature, in this way assisting the preparation 30 of the mixture for further combustion.

The mixture, as it passes through the grid, is subdivided into a large number of jets, each of which is subjected to the heat of the 35 grid, which contacts with most of the gas particles and causes a disassociation of some of the carbon dioxid. The subdivided portions of the gas mixture unite above the grid, and the lighter gases may or may not burn 40 above such grille or screen. If they burn, the combustion is ordinarily more or less fluctuating and intermittent. The chamber 22, as has been indicated, permits the further intermixing of the uniting jets and 45 prepares the gaseous mixture for the final combustion or burning, which occurs at the jet-opening or slot 20, such flame receiving additional oxygen for the carrying on of the combustion from the external atmosphere. 50

Presenting the matter somewhat differently, the mixture of gas and air is burned successively three or four times, being retarded in its passage through the multiple 55 burner so as to be subjected to heating between the combustions, the mixture being also treated with respect to pressure and the intermixing of the ingredients so as to render possible the successive burnings referred to. Owing to the treatment to which the 60 mixture has been subjected before it reaches the last burner-opening 20, the products of combustion there are substantially or practically odoreless, the combustion of the mixture having been perfect, and the flame is 65

steady, receiving oxygen from the outer air for promoting combustion. The bacteria which may have been present are destroyed, and the resulting products of combustion may be employed, if desired, for their sterilizing qualities. 70

The general principles of this improved and novel method and process have been indicated above, but the various steps in the process may be changed more or less and 75 still retain all of the essential and vital features of the method. Consequently, the claims appended hereto should receive a liberal interpretation, in view of the novelty and various features of improvement present 80 in the process.

While I have herein described the burner as being provided with a hollow rectangular cast-metal control-box, it is to be understood that the shape of such box is largely immaterial and that its form may be varied within wide limits. For example, it might be round or of hexagonal or other shape. 85

The structure of the burner herein disclosed is claimed in my co-pending application Serial No. 876,997, filed Dec. 12, 1914. 90

I claim:

1. The method of burning gas in successive combustions, which consists in burning the gaseous mixture more than twice in succession, and commingling the ingredients of the mixture between the successive combustions without the addition of air, substantially as described. 95

2. The method of burning gas in successive combustions, and heating the ingredients of the mixture between the successive combustions and without the addition of air, substantially as described. 100

3. The method of burning gas in a plurality of successive combustions, and heating and commingling the ingredients of the mixture between the successive combustions without the addition of air, substantially as described. 105

4. The method of burning gas, consisting in burning a mixture of gas and air, projecting the products of combustion and the unburned portions of the mixture against a surface to secure their better intermixture, and then again burning the mixture without the addition of air, substantially as described. 110

5. The method of burning gas, consisting in burning a mixture of gas and air, subdividing the products of combustion and the unburned parts of the mixture into small portions, reassembling or collecting such products and parts into a main body without the addition of air, thereby effecting a better intermixture, and burning such body, substantially as described. 120

6. The method of burning gas, consisting in burning a mixture of gas and air, subdividing and simultaneously heating the prod- 125

130

ucts of combustion and the unburned parts of the mixture, reassembling or collecting such products and parts in a main body without the addition of air, thereby effecting 5 their better intermixture, and burning such body, substantially as described.

7. The method of burning gas, consisting in burning a mixture of gas and air, restraining and heating the products of combustion 10 and the unburned portions of the mixture to steady or equalize the pressure, and again burning the mixture without the addition of air, substantially as described.

8. The method of burning gas, consisting 15 in burning a mixture of gas and air, restraining and heating the products of combustion and the unburned portions of the mixture and at the same time securing their better intermixture by playing the flames 20 against a surface, and then again burning the mixture without the addition of air, substantially as described.

9. The method of burning gas, consisting in burning a mixture of gas and air, restraining and heating the products of combustion 25 and the unburned portions of the mixture, again burning the mixture, then additionally restraining and heating the mixture, permitting the gases by their swirling action to become better incorporated one with the other and without the addition of air, and then again burning the mixture, substantially as described.

10. The method of burning gas, consisting 35 in burning a mixture of gas and air, restraining and heating the products of such combustion and the unburned portions of the mixture, again burning such mixture, then breaking up the mixture into small portions 40 and simultaneously heating such parts, then collecting such portions into a main body without the addition of air, and burning such body, substantially as described.

11. The method of burning gas, consisting 45 in burning a mixture of gas and air, restraining and heating the products of such combustion and the unburned portions of the mixture, and at the same time creating a better intermixture of the ingredients by 50 playing the flames against a surface, then burning such mixture without the addition

of air, then dividing the mixture into small portions and simultaneously heating such portions, then collecting such portions into a main body, and finally burning such body, 55 substantially as described.

12. The method of burning gas, consisting in burning a mixture of gas and air, restraining and heating the products of combustion and the unburned portions of the 60 mixture, and at the same time creating a better intermixture of the ingredients by playing the flames of such combustion against a surface, again burning the mixture without the addition of air, restraining and 65 heating the mixture and permitting the gases by their swirling action to become better incorporated with one another, dividing the mixture into small portions and simultaneously heating such portions, then collecting such portions into a main body, and finally burning such body, substantially as 70 described.

13. The method of burning a gaseous mixture consisting in burning the mixture at a 75 primary combustion, impeding the movements of such mixture, and burning such modified mixture without the addition of air.

14. The method of burning a gaseous mixture consisting in burning the mixture at a 80 primary combustion, impeding the movements of and heating such mixture, and burning such modified mixture without the addition of air.

15. The method of burning a gaseous mixture consisting in providing a primary combustion for the mixture and then burning the modified mixture without the addition of air to such mixture.

16. The method of burning a gaseous mixture consisting in providing a primary combustion for the mixture and then burning the modified mixture in a succession of combustions without the addition of air to said mixture.

In witness whereof, I have hereunto signed my name, this 19th day of November, 1914.

WILLIAM K. TWOMEY.
